BLASTING CARTRIDGE

Arthur W. Helmholtz and Dent Ferrell,
Harrisburg, Ill.

Application July 16, 1931. Serial No. 551,085

4 Claims. (Cl. 102—6)

This invention relates to an improved form of cartridge for blasting purposes adaptable to the mechanical pressure system of blasting and covers improvements over our former Patent No. 1,569,226, issued January 12, 1926, relating to a mechanical pressure blasting method and a device for carrying out the method. The present improvements include more particularly a new and novel design of blasting container which has several important advantages over former constructions.

It is one object to obtain a blasting container which is cheaply and easily made.

It is another object to provide a blasting container which is automatically held in the drill or bore hole in the material to be blasted and thus eliminates the objections encountered heretofore of containers or shells being thrown from the bore holes by too shallow a hole or insufficient tamping. The flying of the shell or cartridge of the bore hole from any cause whatsoever is instrumental in damaging the container or shell itself or other machinery in its path and is also dangerous in causing injury to workmen.

It is another object of the improved form of construction to eliminate damage and destruction to the pipe lines connecting this shell to the source of pressure, thus providing for a cheaper cost of operation and maintenance cost.

Other objects and advantages of the present improvements will be more readily understood from the following description taken in connection with the attached drawing, in which

Figure 1 is an elevation illustrating the blasting container in place in a drill hole;

Figure 2 is a longitudinal section of the blasting container;

Figure 3 is a transverse section taken on the plane indicated 3—3 in Figure 2, and

Figure 4 is a transverse section taken on the same plane looking in the opposite direction, as indicated by the arrows 4—4.

In general, blasting shells used in our method are arranged so that the venting of the shell is at the inner end of the bore hole and as a result, when the rupture of the venting disk in the shell occurs, a reaction takes place which tends to force the shell out of the hole and if the hole is too short or the tamping too light, the shell will be readily forced out by the blasting pressure produced. This reaction is also assisted by the expanding gases between the inner end of the shell and the inner end of the drill hole. In such case the shell is very liable

to be blown out with sufficient force to injure the shell itself or machinery or workers in its path.

In the present application the shell or container is a rigid metallic barrel having one end completely closed and the opposite end adapted to hold a removable and renewable venting disk. The shell is of strong material, greater than the venting disk, so that it is substantially indestructible and may be used an indefinite number of times. According to the present improvements the inlet connection from the source of pressure to the shell is at the same end of the shell as the venting disk.

Referring to Figure 1, 10 is the roof of the coal breast, 12 is the floor or bottom and 14 is the coal face. The coal face is undercut as at 16. The drill hole 18 is placed in accordance with the judgment of the workman and is generally directed into the coal face at the top portion and slightly in a diagonally upward direction. An imaginary vertical plane, indicated by a dotted line 20, extends from the inner end of the undercut 16 towards the roof 10 and defines a so-called solid portion of the coal face or breast. The drill hole 18 extends somewhat beyond the plane 20 to accommodate a part of the blasting shell 22 so that the venting end 24 is near the plane 20, just how near will depend somewhat upon the particular nature of coal or material to be blasted. The pipe line 26 extends from the source of pressure to a connection of the shell at the venting end thereof. The remainder of the drill hole 18 is filled with tamping 28. In the present case the tamping is only necessary to prevent loss of gas after venting of the shell and is not required to hold the shell in place. Pipe line 26 communicates with the pressure source and conducts the blasting medium under high pressure, such as 5000 pounds per square inch, to the blasting shell 22 until the rise in pressure in the shell is sufficient to rupture the venting disk and release the gas, whereupon that portion of the coal from the plane 20 to the face 14 is forced outwardly and downwardly and thrown away from the main body of the coal by the comparatively slowly expanding blasting medium.

The operation is entirely safe since there is no combustion reaction, no high temperature of any kind and no noxious gases are created. The operation is similar to hydraulic blasting except that it has the additional advantage of using an expandable medium instead of a non-expandable fluid, such as water.

The container is shown in detail in Figure 2 and

includes a rigid container barrel 22 having an interior cavity 30 on the longitudinal axis of the barrel. The cavity may be offset with respect to the outside diameter of the barrel at its open end, leaving a thinner wall on one side than on the other, as is shown in Figure 2. The open end is provided with an internally-threaded portion 32. The thicker side of the wall is provided with a passage 34 communicating with the cavity 30 and a pipe line 26 having a threaded connection at 36 with the shell 22. An exteriorly threaded shoulder member or throat piece 38 is inserted in the barrel and is preferably cemented in position to insure a tight connection. The inner end of the opening through the shoulder is rounded and tapered, as at 40, to diminish the resistance to flow of the blasting medium from the shell. The blasting medium passes through the circular orifice 42 of the shoulder which is of sufficient area to permit escape of the blasting medium. The outer end of the shoulder 38 has a circular knife edge 44 which is concentric with respect to the axis of the shoulder but is eccentric with respect to the axis of the barrel 22. The knife edge is a ridge of hard metal and makes for a gas-tight joint with the venting disk 46, which is of softer metal. It is necessary, in obtaining a tight metal-to-metal joint between knife edge of shoulder 38 and the disk 46, to avoid relative rotation between the parts, while the disk is being pressed into sealing engagement therewith, and in the present case relative rotation is prevented by means of a hardened pin 48 inserted in the shoulder and extending partly beyond the knife edge 44 so that as the disk 46 is pressed towards the shoulder, the pin 48 will be initially pressed into the disk to prevent relative rotation.

As an additional or alternative manner of preventing rotation of the disk 46, we may use a hardened threaded pin 50 which extends through the barrel and engages a notch 52 in the edge of the disk. In order to press and hold the disk in place against axial displacement and to provide an abutment against which the disk may shear, there is shown a cap member 54. The cap member is a hollow plug, either forged or machined of suitable material, having an external thread for engaging the threaded portion of the barrel. The inner end 56 of the cap member, which presses against the disk 46, is a hardened portion forming an annular edge against which the disk 46 will shear when the desired pressure for rupture is reached. The cap member has a straight circular passage 58 permitting the ruptured portion of the disk 46 to be blown wholly out of the cap member and additional lateral openings 60 are provided to permit the escape of the blasting medium from the cap member.

70

75

It will be apparent that we have described a blasting cartridge which is commercially satisfactory and which, when in use, is less possible to produce injury than previous constructions for similar purposes.

Various modifications may be resorted to without departing from the spirit of our invention as expressed in the appended claims.

We claim:

1. Blasting apparatus comprising a closed container adapted to fit in the drill hole, said container having rigid walls integrally closing the inner end of said container adjacent the inner end of said drill hole and a rupturable wall at the outer end of said container, a pipe line connected to the outer end of said container adapted to deliver gas under pressure into said container whereby the release of said gas from said container through rupture of said rupturable wall tends to hold said container in said drill hole and prevent buckling of said pipe.

2. The process of shooting coal or like material which comprises, providing a drill hole in the material to be shot, providing a shell in said drill hole containing a confined non-explosive fluid medium under relatively high pressure, causing the release of said medium only at a point adjacent the outer end of said shell whereby to exert in addition to a shooting force, a force acting to hold said shell in said drill hole.

3. The process of shooting coal or like material which comprises, providing a drill hole in the material to be shot, providing a shell in said drill hole containing a non-explosive fluid medium under pressure confined by a rupturable wall facing outwardly of said drill hole, thereafter providing a predetermined high fluid pressure within said shell and causing the rupture of said wall and the release of said fluid only in the outward direction of said drill hole whereby to exert in addition to a shooting force, a force acting to hold said shell in said drill hole.

4. The process of shooting coal or like material which comprises, providing a drill hole in the material to be shot, providing a shell in said drill hole containing a non-explosive fluid medium under pressure confined by a rupturable wall facing outwardly of said drill hole, forcing fluid under pressure into said shell until a predetermined high pressure is reached therein and then causing said wall to rupture and to release said fluid only in the outward direction of said drill hole whereby to exert in addition to a shooting force, a force acting to hold said shell in said drill hole.

ARTHUR W. HELMHOLTZ.
